UNITED STATES PATENT OFFICE.

GOTTFRIED WELGER, OF SEEHAUSEN, GERMANY.

BALING PRESS.

1,412,021.

Specification of Letters Patent. Patented Apr. 4, 1922.

Application filed August 5, 1920. Serial No. 401,453.

To all whom it may concern:

Be it known that I, GOTTFRIED WELGER, manufacturer, residing at Seehausen, Wanzeben, Republic of Germany, have invented 5 certain new and useful Improvements in Baling Presses, (for which I have filed application in Germany March 1, 1919; Netherlands, June 1, 1920; Switzerland, June 2, 1920,) of which the following is a specification.

My invention relates to improvements in baling presses and more particularly in baling presses for short materials such for example as chaff. As is known in the art one 15 type of baling press of this class is constructed with a vertical or inclined passage within which the material is compressed by means of a reciprocating piston, and from which it is discharged in the form of a bale. 20 For producing uniform bales, partitions must be placed in the passage at certain intervals which border the bales and permit binding thereof. One of the objects of the improvements is to provide means for 25 throwing the said partitions into the said passage, which means are so constructed as to permit rapid and reliable operation, the partitions being guided in such a way that they are not arrested in their movement by 30 being inserted angularly. With this object in view my invention consists in providing a spring pressed throwing member in front of the opening of the passage and on a table provided for inserting the partitions which 35 throwing member is adapted to engage the rear of the partitions and to throw the same in a direction passing through its plan.

For the purpose of explaining the invention several examples embodying the same 40 have been shown in the accompanying drawings, in which the same letters of reference have been used in all the views to indicate corresponding parts.

In said drawings,

45 Fig. 1, is a vertical cross-section of the press,

Fig. 2, is a horizontal section taken on the line A—A of Fig. 1;

Fig. 3, is a partial vertical cross-section 50 showing a modification of the invention, and

Figs. 4 and 5, are vertical cross-sections showing further modifications.

Fig. 6 is a vertical cross section of the press showing the operating levers.

55 Fig. 7 is a horizontal section taken on a line located above the said levers.

Figs. 8 and 9 are vertical cross sections of further modifications of the invention.

Fig. 10 is a vertical section of the means for feeding boards successively to the slide. 60

Referring to the example shown in Figs. 1 and 2, the baling press comprises a vertical trunk 1 adapted to receive the material to be baled by means of a reciprocating piston (not shown). The trunk is provided 65 with a horizontal slit 3 for inserting the partitions 2 therethrough and in front of the said slit a horizontal table 4 is provided for placing the partitions 2 thereon. The table is formed with lateral flanges 6 providing 70 guides for the partitions and the flanges are formed with longitudinal slits 5 providing guides for a throwing member such as slide 7. To the outer ends of the said slide, springs 8 are attached which are secured at 75 their opposite ends to fixed parts of the trunk 1. The springs are adapted to move the partitions within their planes and into the trunk. For inserting a partition 2 into the trunk 1 the slide 7 is retracted in the direction of the arrow α by means of a handle 9 secured thereto or by means of operating levers 19 and 13 (Figs. 6 and 7) engaging the outer ends thereof, whereupon the partition 2 is placed on the table 4. Now the 80 slide is released, so that the springs 8 throw the partitions through the slit 3 and into the trunk and on the surface of the material.

In Fig. 3 I have shown a modification of the invention in which locking means are 90 provided for holding the slide 7 in retracted position. As shown the locking means consists of a locking lever 10 which is held in locking position by a spring 11, and which is adapted to be rocked in releasing by 95 pressing on the front end 12 thereof.

When releasing the throwing slide while the compressing piston is not in proper position, the partition, the wall of the trunk, or the piston might be injured. Therefore 100 I prefer to provide an operative connection between the piston and the unlocking means for the throwing slide. Such means are shown by way of example in Fig. 4. As shown in the said figure the locking member 105 10¹ is adapted to be connected with the piston 14 by a hand operated lever 13, so that the piston releases the slide 7 when moving away from the slit 3. As shown the rocker 10¹ is extended rearwards of its fulcrum 15 110 and it is connected with the piston 14 by a link 16 having a hook shaped upper end

adapted to engage a trunnion 17 provided on the piston. When the piston 14 moves upwards, and the lever 13 is rocked into the position shown in Fig. 4, the link 16 is set 5 in position for engagement with the trunnion 17 by means of a rocker 21 connected with the lever 13 by a link 20. The front end of the rocker 21 is enlarged sufficiently to securely engage the link 16 for rocking 10 the same. Upon upward movement of the piston 14 the link 16 is carried along so as to set the rocker 10¹ in releasing position. Fig. 4 shows the parts in the position in which the rocker 10¹ has released the slide 7 and 15 the slide has thrown a partition 2 into the trunk 1. The following operation consists in setting the slide 7 in position for throwing another partition, and for this purpose the hand operated lever 13 is rocked in the direction of the arrow y. The slide 7 is re- 20 tracted to the right by means of the lever 13 and a short lever 19 keyed to the opposite end of the rock shaft 18 to which the lever 13 is secured. In the retracted position 25 the slide 7 is again locked by the pawl 10¹. Finally a new partition is placed on the table 4. The link 16 is automatically rocked out of operative position relatively to the piston by means of a spring 22, when the lever 13 30 and the rocker 21 are rocked to the right.

I wish it to be understood, that my invention is not limited to the construction shown in Fig. 4, and more particularly to the construction in which the locking mech- 35 anism 10¹ is set in position for releasing the slide 7 upon the upward stroke of the piston 14. Furthermore, the invention is not limited to the construction in which the slide 7 is retracted by hand. In order that the slide 40 7 can be returned to its locked position by the piston, there is connected to the trunnion 17 a triangular element, the inclined surface of which acts on lever 20, (see Fig. 8). In the downward movement of the piston, the 45 lever 20 and lever 19 connected thereto are moved to the right by the cam action of the inclined surface, and in this movement the levers 19 and 20 carry along the slide 7 into its locked position.

50 In Fig. 5 I have shown a modification of the invention in which the locking member 10² is set in non-locking position by means of the material being baled. As shown a star wheel 23 is provided on the part of the 55 trunk where the material is compressed, which star wheel is made to be rotated by the material moving downwards. To the star wheel a pin 24 is secured which upon rotation of the star wheel lifts a lever 25 60 connected by a link 26 with a rocker 27 carrying the locking member 10². In a modification of the invention illustrated in Figure 9, the lever 25 is connected with means such as check rod 26 having a hooked shaped up- 65 per end for engaging a lip on the rod 16

for setting the link 16 in inoperative position relatively to the trunnion 17. The rotation of wheel 23 raises the rod 25 and also the rod 26. When the hook shaped upper end of the check rod 26 is thus lifted above the lip of the rod 26 a spring 30 compressed between a stationary frame and the rod 16 will move the latter into the position indicated in Figure 4, or to operative position. In its upward movement the piston encountering rod 16 can thus rock the lock 10 about its pivot 15 and release the slide 7. At the lower part of the rod 16 there is connected a triangular element having an inclined surface which can be forced back by the piston, the rod 16 thus being moved into the locked position where it is retained by the check rod 26. This movement of the triangular element also moves lever 20 in the same direction and carries the lever 19 and the slide 85 7 into the starting position.

A further modification consists in placing the partitions 2 in a pile above the table 4, as illustrated in Figure 10, in which case the throwing member 7 inserts upon its operative stroke the lowermost partition member. Slide 7 is made of such length that during this operative movement it holds back the remaining boards of the pile until the slide is again carried back to the starting position, when the next partition drops on the table and in position for being thrown by the slide 7 upon the return stroke thereof.

I claim:

1. In a baling press, the combination with a vertically disposed trunk having a transverse slit in its wall, and a compressing member adapted to reciprocate in said trunk, of means for guiding a partition to be inserted through said slit, a throwing member 100 slidably mounted in said means for throwing a partition through said slit and into the trunk, and spring means connected to opposite ends of said throwing member for imparting throwing movement thereto. 105
2. In a baling press, the combination with a vertically disposed trunk having a transverse slit in its wall, and a compressing member adapted to reciprocate in said trunk, of means for guiding a partition to be inserted through said slit, power operated means adapted to throw said partition through said slit and into the trunk, means for locking said power operated means in position ready for throwing, devices controlled by said compressing member and operative when said compressing member is approaching the top of its stroke to set said locking means in releasing position, and hand operated means to set said devices in 115 position for operation by the compressing member. 120
3. In a baling press, the combination with a trunk having a transverse slit in its wall, and a compressing member, of means for 130

guiding a partition to be inserted through said slit, power operated means adapted to insert said partition, means for locking said power operated means in position ready for 5 throwing, devices controlled by said compressing member and operative when said compressing member is away from said slit to set said locking means in releasing position, means to set said devices in position 10 for operation by the compressing member, and mechanism connected with said setting means and coacting with said compressing member for automatically retracting said power operated member in position ready 15 for throwing.

4. In a baling press, the combination, with

a trunk having a transverse slit in its wall, and a compressing member, of means for guiding a partition to be inserted through said slit, power operated means adapted to 20 insert said partition, means for locking said power operated means in position ready for throwing, and a rotary member controlled by the material being baled and operatively connected with said locking means for setting the same in nonlocking position.

In testimony whereof I have affixed my signature in presence of two witnesses.

GOTTFRIED WELGER.
